WILLIAM H. FAUBER, OF CHICAGO, ILLINOIS.

DESIGN FOR A CRANK-ARM FOR VELOCIPEDES.

SPECIFICATION forming part of Design No. 29,525, dated October 18, 1898.

Application filed September 18, 1897. Serial No. 652,198. Term of patent 7 years.

To all whom it may concern:

Be it known that I, WILLIAM H. FAUBER, a citizen of the United States, residing in the city of Chicago, county of Cook, and State of Illinois, have invented a new and original Design for Crank-Arms for Velocipedes, of which the following is a specification, reference being had to the accompanying drawings, forming a part thereof.

In said drawings, Figure 1 is a front or face view of a crank-arm made in accordance with my novel design. Fig. 2 is a side view thereof, showing the crank-shaft. Fig. 3 shows a cross-section of the arm outside of its point of attachment to the shaft.

My novel design is herein shown as applied to a crank arm and shaft for velocipedes.

Said crank-arm is provided with four flat oblique faces, making the same of diamond or lozenge shape in cross-sectional form, and is joined to the shaft or axle by a right-angled bend. The shaft or axle is of cylindric form and is provided just inside of the point at which it joins the arm with a concentric cylindric screw-threaded enlargement.

The arm is provided on its outer end with a circular enlargement or hub, within which is formed a circular aperture, the central axis of which is parallel with the central axis of the shaft. Said enlargement or hub is provided on two of its opposite sides with parallel flat faces at right angles to the axis of the aperture therein. Said arm is of greatest width at its point of attachment to the shaft and tapers gradually toward the outer end hereof. The oblique faces of said arm are so arranged that two of its opposite corners or angles will be in the plane of rotation of the arm, and a plane passing through the two opposite corners or angles will lie at right angles to said first-mentioned plane or parallel with the axis of the shaft. The faces of said arm are also so arranged that the width between the two opposite angles or corners which lie in the plane of rotation of the arm is greater than the distance between the angles which lie parallel with the shaft-axis, or, in other words, said arm is of greater width from side to side than from its inner to its outer face.

The shape of the parts at the junction of

the arm proper and the shaft is as follows: Said shaft is cylindric from its extreme inner end to the point at which the arm intersects the same, and the outer shaft and arm at 55 their point of intersection are furnished with a convex or spherically - rounded surface which forms a smooth continuation of the cylindric surface of the shaft, the said convex surface being so shaped that, as seen in 60 side view, the outer line of the arm is joined to the line of the shaft by a circular quadrant tangent to both of said parts. The two flat outer oblique faces of the arm are continued along the arm until they intersect at 65 a slight angle the convex or rounded surface referred to and the intersection being defined by angles which follow approximately semicircular lines. Such semicircular lines define the ends of the flat surfaces, each semicircular line starting at the side face or angle of the arm and terminating at the outer central angle or corner thereof. By reason of the convex or rounded form of the parts at the junction of the shaft and arm these two 70 semicircular curved lines are located about opposite the central axis of the shaft. The inner oblique faces of the arm extend to the adjacent convex surface of the shaft and are merged by concave or inwardly-curved surfaces into the convex surface of said shaft. 75

The side faces of the arm, immediately adjacent to the hub, at the outer end thereof, are convexly rounded, and the oblique surfaces at both the inner and outer faces of the 80 arm terminate in convex outwardly-curved surfaces which intersect both the lateral convexly-rounded surfaces of the arm and the flat inner and outer faces of the boss to form angles which are defined by curved lines, 85 the angles at the side faces being on oppositely-curved lines which intersect at the central angular line of the arm and diverge until they merge into the circular line which defines the end of the boss, as seen in Fig. 1, 90 while the angles at the sides of the boss diverge from the lateral angle of the arm to the front and rear faces of the boss, and thereby give to the convexly-rounded side faces of the arm approximately the form of 95 a triangle, as seen in Fig. 2.

The essential or characteristic feature of

29,525

my design is embraced in the flat oblique faces upon the arm in connection with a convexly-rounded surface at the junction of the arm and shaft, such as would be produced were the shaft and arm originally made cylindric and then bent at an angle, said flat oblique faces being extended so as to intersect the rounded surface, and thereby form two angles which follow approximately semicircular lines from the center angle to the

side angles of the lozenge - shaped arm, as clearly seen in the drawings.

I claim as my design—

The design for a crank-arm for velocipedes substantially as shown and described.

WILLIAM H. FAUBER.
